UNITED STATES PATENT OFFICE.

WILLIAM L. NIES AND CHARLES R. BIRDSEY, OF CHICAGO, ILLINOIS, ASSIGNEES TO
UNITED STATES GYPSUM COMPANY, OF CHICAGO, ILLINOIS, A CORPORATION OF
NEW JERSEY.

FLOOR CONSTRUCTION OR THE LIKE.

1,313,500.

Specification of Letters Patent.

Patented Aug. 19, 1919.

Application filed October 2, 1916. Serial No. 123,422.

To all whom it may concern:

Be it known that we, WILLIAM L. NIES and CHARLES R. BIRDSEY, citizens of the United States, residing at Chicago, in the 5 county of Cook and State of Illinois, have jointly invented certain new and useful Improvements in Floor Constructions or the like, of which the following is a description.

Our invention belongs to that general 10 class of devices or manufactures known as floor constructions, and which more particularly relates to an improved floor dome and filler block, each of suitable material and form, adapted for the use in the construction 15 of reinforced concrete floors or the like. The invention has among its objects the production of the domes and filler blocks of the kind described for construction purposes, that are simple, durable, efficient, and satisfactory, for use wherever found applicable. 20 It has particularly as an object the production of devices of the kind described that may be employed in the construction of fireproof floors, roofs, and the like, where 25 suitable reinforced concrete, or its equivalent, is employed.

The invention has as additional objects 30 the production of the devices described, which may be substantially or inexpensively 35 constructed, and which may be safely, conveniently and economically transported to where the same are to be used, and there installed. The preferred form of domes and filler blocks are constructed of gypsum rock, known as plaster of Paris, or any equivalent, which may be suitably reinforced, if 40 desired. Our particular form of device, although of light weight, is of such durability that it may be manufactured, handled, transported and set, as hereafter described, with a minimum of fracturing or 45 breaking. When accidentally fractured, however, in handling, setting, or after set, even though fractured to a considerable extent, the domes or filler blocks are usable without in any way impairing the construction of the building. The invention has as 50 a still further object the production of a floor construction in which the under surface or ceiling of the apartment below the floor will present a continuous surface with the same material, and with the same characteristics, to which plaster, if desired, is di-

rectly applied without the application of wooden or metal lath or fabric of any kind. 55

Many other objects and advantages of the construction herein shown and described will be obvious to those skilled in the art from the disclosure herein made.

To this end our invention consists in the 60 novel construction, arrangement and combination of parts herein shown and described, and more particularly pointed out in the claims.

In the drawings, wherein like reference 65 characters indicate like or corresponding parts,

Figure 1 is a perspective view of a portion of a floor construction embodying the 70 domes and filler blocks;

Fig. 2 is a sectional view through two of the domes and the filler block carried thereby;

Fig. 3 is a sectional view taken lengthwise through one of the domes; 75

Fig. 4 is a sectional view through a portion of a floor construction, illustrating a slightly modified shape of dome;

Fig. 5 is a longitudinal sectional view 80 through one of the same domes, and

Fig. 6 is a plan of the same.

Referring to the drawings, in which are shown floor constructions embodying our domes and filler blocks, it may be first mentioned that in constructing floors of concrete 85 or like material, it is desirable to have the floor of minimum weight consistent with strength and durability. It is also desirable to have the floors constructed so that the concrete substantially forms properly designed concrete beams which are reinforced with suitable reinforcement to increase the tensile strength of the structure when needed. In making up the floor, our domes and filler plates, or blocks, are employed, 90 the same being suitably set and supported, and the concrete then deposited around and over the top of the same to form the floor.

The domes are constructed of a body mass composed of calcined calcium sulfate, or 100 gypsum rock, known as plaster of Paris, which when mixed with water, forms a liquid mass, which by crystalline action, quickly sets into a rigid body, the same being suitably molded into the desired form 105 and suitably reinforced while in the liquid

state with a suitable reinforcing fabric. Each dome or body consists of a top 1, sides 2, 2, bottom 4 and ends 3, 3, making a closed box form. The top and sides, and if desired, the bottom, are suitably reinforced, as for example, by a wire fabric 5. The dome is preferably cast with the wire fabric 5 in the same, as mentioned, and so that it lies substantially close to the inner or lower face of the top 1, and extends close to the exterior at each side, and thence down. By extending it close to the exterior of the sides, the same is not liable to pull the side walls in or cause them to break down when a load is put on the top during the construction. In most cases we prefer to extend the same across the bottom, overlapping the two ends, as most clearly illustrated in Fig. 2. In constructing the dome, the top, the two sides and the two ends are preferably cast integral in a mold in any suitable manner, after which the same, when set, is removed from the mold, and the bottom suitably puddled in. However, any one of the walls may be puddled in to form the complete body of the dome, if desired, this being a matter of preference. Where the bottom is puddled or cast in as described, we preferably provide a groove 7 in one part, as shown in the body of the dome, about the interior faces, and the bead 8 on the other part, as shown on the bottom, arranged to interengage with the groove in the body of the dome, so that the bottom is securely locked in place. In the dome shown the end partitions are set slightly in from the end at the top, and at an angle. We have shown recesses or hand holes 6 in the ends of a size to fit the fingers, the same forming substantially handles at the ends, so that the domes are easily handled and carried about. One end is preferably formed with an opening entirely through to prevent escape of air in puddling in the last wall. The sides and such other portion as may be desired are preferably constructed on the exterior to engage with and be engaged by the concrete, so that the domes are locked in place and a secure construction obtained. For this purpose we have shown grooves 10 arranged on each side of the domes, and extending lengthwise thereof.

In using the domes, the same are preferably spaced, one from the other, at their sides, and arranged with their ends either abutting or substantially close. To fill the space at the bottom, we provide the filler blocks 11, of the same material as the dome, which may be suitably reinforced by wire fabric 13, or its equivalent, if desired. These blocks are preferably arranged with a face 12 beveled or arranged to rest upon and be supported by the outwardly flared lower edge 9, of the domes, so that the domes being locked in place, by engaging the concrete

may support the filler blocks 11. In Fig. 1 a partially constructed floor is shown, in which 16 represents the floor surface of the concrete, which is poured upon and between the domes, so as to substantially form beams 17, which may be suitably reinforced by the reinforcing rods 15. It may be mentioned that in constructing the floor, a suitable temporary supporting structure is provided, as for example as indicated in Fig. 2, by the parts 14, shown in dotted lines, which temporary structure carries the domes and filler blocks until the concrete has been poured and has set sufficiently to be self-supporting, after which the framework may be removed. Plaster 18 (see Fig. 1) may then be applied to the bottom or lower face of the domes and filler blocks. It will be particularly noted in this connection that the domes and filler blocks form an ideal base upon which the plaster 18 may be applied, and the same being all of the same material, the plaster is uniformly supported, affording a most satisfactory completed construction. The concrete engaging in the grooves 10 supports the domes, and these support the flared blocks 11, as described. The domes being very durable, the same are not easily fractured in handling, as previously set forth. In this connection it may be mentioned that after the same are set or placed, and supported by the temporary structure, by placing suitable planks over the same, the laborers with wheelbarrows of concrete may, if necessary, walk back and forth across the domes in applying the concrete, without fracturing them. Should any one be fractured; however, owing to the reinforcement, the utility of the same in practically every case is not impaired, and the same, even if fractured, may be left in place.

The construction of domes and blocks shown in Figs. 4, 5 and 6, is substantially similar to that previously described. The shape of the domes, however, is a little different, and various other minor changes are incorporated in the same. Referring to these figures, 21 represents the top, 22 the sides, and 24 the bottom of the domes, which are provided with the ends 23. Reinforcement 25 of fabric is employed as shown. One or both ends may be puddled in, the same being formed with hand holes 26, and one part with bead 28, and the other with co-operating groove 27. In this case the sides are inclined and sides and top are provided with a series of recesses or depressions 30, serving the same purpose as the grooves 10 in the other construction. The filler blocks 31 are substantially similar to those previously described, and may be reinforced by fabric 33. Owing to the change in form or shape of the domes, however, the concrete beams 37 of the floor 36, which are reinforced as at 35, are of slightly different shape. This

construction, however, permits the plaster 38 to be spread on a surface which is all of the same material, affording a most satisfactory construction.

5 It will be noted that with this style of dome, that while the same may be manufactured at the construction job, or where to be used, owing to their convenient construction and durability, they may be manufactured where desired, and be very compactly stacked and shipped. While of great strength, they are of comparatively light weight, so that each one may be easily handled by one man, the hand holes described making the handling most convenient. They are fireproof, as is the concrete, so that an extremely fireproof construction is obtained that is of light weight compared with the strength, and which is economical 20 to construct. It is to be noted that gypsum being a fireproof material of high order, in this method of construction adds more fireproofing, in most cases at least approximately one inch additional fireproofing, to 25 the reinforcing steel over other types of construction.

Having thus described our invention, it is obvious that various immaterial modifications may be made in the same without departing from the spirit of our invention; hence we do not wish to be understood as limiting ourselves to the exact form, construction, arrangement and combination of parts herein shown and described, or uses 35 mentioned.

What we claim as new and desire to secure by Letters Patent is:—

1. A dome of the kind described, comprising a box-like body having integrally formed top, side and end walls, a bottom partition wall arranged on the interior thereof near the lower edges of said walls, the under face of said partition wall extending flush with the bottom edges of said walls, 40 the partition and adjoining parts of the body being arranged to interlock.

2. A dome of the kind described consisting of a hollow box like body, having side, end, top and bottom walls permanently connected together and constructed with a continuous reinforcement of wire fabric embedded therein and extending completely around the top, sides, and bottom intermedi-

ate the ends thereof, the sides of the body extending at an inward inclination toward each other.

3. A dome of the kind described, comprising a hollow body having a top, bottom, and side and end walls, said end walls being inclined upwardly from the bottom and provided with openings near the upper portions thereof constituting hand holes, said top and side walls extending over and beyond the upper portion of the end walls.

4. A dome of the kind described consisting of a hollow box like body having side, end, top and bottom walls, permanently connected together and constructed with a continuous reinforcement of wire fabric embedded therein and extending completely around the top, sides and bottom, said wire reinforcement in the top extending near the underside thereof, and extending to adjacent the outer faces of the sides.

5. A dome of the kind described comprising a box like body having integrally formed top, side and end walls, and a bottom partition wall located interiorly of the box like body near the lower edges of the side and end walls thereof, the under face of said partition wall extending flush with the bottom edges of the side and end walls of the box like body, and marginal portions of the said partition and adjoining parts of the side and end walls of the box like body being provided with interfitting tongue and grooved portions.

6. A dome of the kind described consisting of a hollow box like body having integrally formed top, side and end walls, a bottom partition wall arranged at the interior of the box like body near the lower edges of the side and end walls of the box like body, said end walls extending upward at an inward inclination toward each other from the outer ends of the partition, and adjoining the top wall intermediate the ends thereof.

In testimony whereof, we have hereunto signed our names in the presence of two 100 subscribing witnesses.
